E shelf labels, posted at e-shelf-labels.com, posted on Sep. 19, 2020, site visited Nov. 17, 2021. online, available from internet: <https://web.archive.org/web/20200919160747/https://www.e-shelf-labels.com/news/news-about-labels-and-signage/solum-as-new-solution-partner-of-e-shelf-labels.html> (Year: 2020).*

Primary Examiner — Catherine Ho*(74) Attorney, Agent, or Firm* — Morgan, Lewis & Bockius LLP(57) **CLAIM**

The ornamental design for an electronic shelf label, as shown and described.

DESCRIPTION

FIG. 1 is a front perspective view of an electronic shelf label showing the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate unclaimed subject matter and form no part of the claimed design.

1 Claim, 6 Drawing Sheets(56)
